CHARLES M. MILES AND GEORGE W. REMSEN, OF LINCOLN, DELAWARE.

Letters Patent No. 77,514, dated May 5, 1868.

IMPROVEMENT IN LAMP-BURNERS.

The Schedule referred to in these Letters Patent and making part of the same.

TO ALL WHOM IT MAY CONCERN:

Be it known that we, CHARLES M. MILES and GEORGE W. REMSEN, of Lincoln, in the county of Sussex, and State of Delaware, have invented a new and improved Lamp-Burner; and we do hereby declare that the following is a full, clear, and exact description thereof, which will enable others skilled in the art to make and use the same, reference being had to the accompanying drawings forming part of this specification, in which—

Figure 1 represents a side elevation of our improved lamp-burner.

Figure 2 is a longitudinal central section of the same.

Figure 3 is a horizontal section of the same, taken on the plane of the line $z z$, fig. 1.

Figure 4 is a horizontal section of the same, taken on the plane of the line $y y$, fig. 1.

Similar letters of reference indicate corresponding parts.

This invention relates to a new burner for petroleum and other lamps, and consists, first, in the arrangement of a turret between the cap and the ordinary body of the burner, said turret having holes, that can be closed by a suitable sliding gate, and through which a match may be applied to the wick for the purpose of lighting the lamp without removing the chimney.

The invention consists, second, in arranging the aforesaid sliding gate in a cam-track, so that it cannot be spontaneously opened by the jerking motion of cars or vessels on which such lamp may be held.

The invention consists, third, in arranging below the dead-air chamber, through which the wick-tube passes, and in which the feed-ratchet is arranged, and which is fully secluded from the reservoir below, and from the air above, a perforated supporting-ring, through the large holes of which the reservoir may be filled, and in having small holes through this same ring, to allow the escape of gases from and the passage of air into the reservoir. The said small holes are protected by a guard on the outside, whereby a flame or spark is prevented from entering the oil.

A, in the drawing, represents the body part of an ordinary or suitable lamp-burner. Through it passes the wick-tube B, as usual, and in it are the bearings for the ratchet-shaft C. Above and below the ratchet-shaft are partitions across the body, which are either both, or at least one, perfectly unperforated, so that no flame can pass from the flame above into the reservoir below. The body A carries a cylindrical or prismatic turret, D, on top of which the ordinary cap E and the chimney-support are arranged.

The turret D is perforated, to allow the application, through the hole or holes, of a match, so that the lamp can be lighted without removing the chimney, as indicated by red lines in fig. 2. The hole or holes in the turret can be closed by a sliding gate of suitable construction, or a perforated ring, F, can be arranged around the turret for that purpose. In the latter case, the parts D and F are connected by means of pins a , on one part, fitting into slots, b , in the other part, as shown in fig. 2.

The slots we prefer to have inclined, so that the ring-gate F would have to be somewhat raised when turned, to bring its hole or holes in line with those in D, whereby the spontaneous opening of the holes by the motion of a car or vessel is avoided. The ring or slide F may be operated by means of a suitable knob or knobs, $c c$.

Between the body A and the ring G, which is fitted around the mouth of the oil-reservoir, may be fitted an upright chamber, H, open at the lower end, which can, if desired, be detached from A or not.

In the upper part of the chamber H are minute perforations, $d d$, through which gases may escape from the reservoir, and through which fresh air may enter the latter. The holes are protected by a suspended guard, e, as shown in fig. 2, so that sparks or a flame cannot enter the reservoir.

The lower part of the chamber H may also have perforations, $f f$, to allow the filling of the reservoir, such holes being closed, if desired, by means of a sliding gate or ring, I, which may operate in a similar manner as the ring F does around the turret D.

The main advantage of this invention above others is, that the flame cannot enter the reservoir, that the chimney need never be taken off, and that the gases from the reservoir can freely escape.

Either all the improvements together, or any one or more of them, can be applied advantageously on a burner.

Having thus described our invention, we claim as new, and desire to secure by Letters Patent—
1. The chamber H and annular slide I, having openings f, and outlets d, when said outlets d are protected by guard e, all constructed and arranged to operate in the manner and for the purpose set forth.

2. The combination, in a lamp-burner, of the perforated turret D, provided with slide F, dead-air chamber A, perforated chamber H, and annular slide I, when said chamber H is provided with outlets d, which are protected by a guard e, all constructed, arranged, and operating as described, for the purpose specified.

3. The lamp-burner, constructed as described, and consisting of the cap E, wick-tube B, perforated turret D, having slot b, perforated annular slide F I, having pins a, dead-air chamber A, perforated chamber H f, having outlets d, guard e, and ring G, all constructed and arranged to operate as set forth.

The above specification of our invention signed by us, this twenty-ninth day of January, 1868.

CHARLES M. MILES,
GEORGE W. REMSEN.
